UNITED STATES PATENT OFFICE.

CHARLES EHRLER, OF ROLLA, MISSOURI.

SHOTGUN-BARREL ATTACHMENT.

1,089,403.

Specification of Letters Patent. Patented Mar. 10, 1914.

Application filed June 30, 1913. Serial No. 776,608.

To all whom it may concern:

Be it known that I, CHARLES EHRLER, a citizen of the United States, and a resident of Rolla, in the county of Phelps and State 5 of Missouri, have invented certain new and useful Improvements in Shotgun-Barrel Attachments, of which the following is a specification, reference being had to the accompanying drawing.

10 One of the principal objects of the invention is to provide a muzzle attachment for a shotgun barrel which will slightly elongate the barrel and provide a choke bore to give greater accuracy for short range 15 shooting.

Another object of the invention is to provide a choke bore attachment for the muzzle end of a cylinder bore shotgun which by giving greater length to the barrel and by 20 contracting the muzzle end of the attachment slightly, the shot are prevented from scattering, thus assuring a gun of great accuracy for short range shooting.

These and other objects may be attained 25 by means of the construction illustrated in the accompanying drawing, in which:

Figure 1 is a top plan view of an attachment made in accordance with my invention and shown connected to the muzzle end of 30 a cylinder bore gun barrel; Fig. 2 is an enlarged central vertical longitudinal section of the attachment showing the muzzle end of a gun barrel in position to be inserted within the attachment; Fig. 3 is a front end 35 elevation of the attachment.

Referring to the drawing, the numeral 1 designates the muzzle end of a gun barrel of smooth cylindrical bore and 2 is the sight on the end of said gun barrel.

40 My attachment comprises an extended barrel portion 3 having a threaded sight 4 connected thereto near the muzzle end. The bore 5 of the attachment is contracted at its muzzle end 6 to form what is known as 45 a choke bore. The rear end of the attachment is slightly enlarged as at 7 and provided with a smooth socket 8 having an annular shoulder 9 at its front portion. An annular recess 10 is formed in the attachment, said recess 10 communicating with a sight opening 11 at the top thereof, said opening being formed in the flattened top portion 12 which permits the sight opening 11 to extend entirely through the attachment. The socket 8 is separated at its lower 55 side to form a slot between the two lugs 13

and said lugs are separated one from the other from the point 14 to the point 15 sufficient to permit the sight 2 on the gun barrel to be passed between them until the sight is 60 disposed within the recess 10 when the sight may be rotated until it assumes a position within the sight opening 11.

To give greater resiliency to the socket member of the attachment and to permit 65 it to be clamped firmly to the muzzle end of the gun barrel a saw kerf or slot 16 extends from the shoulder 15 a slight distance toward the muzzle end of the attachment. A capstan screw 17 provided with holes 18 70 is fitted in threaded openings in the spaced lugs 13 and when the attachment is connected to the muzzle end of the gun barrel, this capstan screw is turned to firmly clamp the attachment to the gun barrel with the 75 muzzle end 19 seated firmly against the shoulder 9 and the sight 2 centered in the sight opening 11 in longitudinal alinement with the sight 4. The shoulder 9 is of the required depth to assure the inner bore of 80 the gun barrel and the choke bore of the attachment to be in perfect alinement so that the load in passing through the barrel will not meet with any obstruction.

From the foregoing, it will be obvious 85 that an attachment made in accordance with my invention may be quickly clamped to the end of a cylindrical gun barrel for the purpose of giving greater direction and condensation to a load of shot and to insure 90 accurate short range shooting. The attachment may be quickly connected to a gun barrel and quickly detached therefrom whenever required and said attachment may be connected to any standard size barrel and 95 firmly clamped in position. If desired, however, different sizes of the attachment may be made for different sizes of gun barrels.

I claim:

1. An attachment for the muzzle end of 100 a shotgun barrel comprising a choke bore barrel extension, a socket at the rear end of said barrel extension, a recess for the sight of the gun barrel, said socket being provided with a shoulder for receiving the muzzle end of the gun barrel and said socket being provided with lugs, and an adjusting screw for clamping the attachment to a gun barrel. 105

2. A shot gun attachment comprising an extended choke bore barrel, a socket in the 110 rear end of said barrel, said socket being divided at its lower end and provided with

spaced lugs, a screw for drawing said lugs together for clamping the attachment to a gun barrel, an annular recess for permitting the sight on the muzzle end of the gun barrel to be positioned therein, said socket being provided with a slot or saw kerf to give greater resiliency to the two clamping members.

3. A shotgun barrel attachment comprising an extension designed to be clamped to the muzzle end of a gun barrel, said extension having a choke bore barrel therein, and an enlarged socket at its rear end, said socket being separated at its lower side to

permit the sight on the gun barrel to pass ¹⁵ into the same and said socket being provided with an annular recess for said sight, said recess communicating with a sight opening at the top of the attachment for the sight on the gun barrel, and means for clamping ²⁰ the attachment to the muzzle end of the gun.

In testimony whereof I affix my signature, in the presence of two witnesses.

CHARLES EHRLER.
